UNITED STATES PATENT OFFICE.

EDWARD ROSE, OF MAMARONECK, NEW YORK, ASSIGNOR TO THE YALE & TOWNE MANUFACTURING COMPANY, OF STAMFORD, CONNECTICUT.

MULTIPLE-KEY LOCK.

1,057,884.

Specification of Letters Patent.

Patented Apr. 1, 1913.

Application filed May 14, 1912. Serial No. 697,269.

To all whom it may concern:

Be it known that I, EDWARD ROSE, a citizen of the United States, residing at Mamaroneck, in the county of Westchester 5 and State of New York, have invented certain new and useful Improvements in Multiple-Key Locks; and I do hereby declare the following to be a full, clear, and exact description of the invention, such as 10 will enable others skilled in the art to which it appertains to make and use the same.

My invention relates to an improvement in locks, the object being to provide a multiple key lock with mechanism that may be 15 operated only by a shut out key, so that when the bolt is projected by said shut out key, it cannot be retracted either by the change or master keys.

A further object is to provide means operated by said shut out key for locking the tumblers against movement, and also for deadlocking the bolt whereby picking the lock will be absolutely prevented.

A further object is to provide means whereby high bitted change tumblers may be operated by a low bitted master key.

A further object is to provide an improved anti-friction latch actuating device between the knob spindle and latch bolt.

With these and other objects in view my invention consists in the parts and combination of parts as will be more fully described and pointed out in the claims.

In the accompanying drawings, Figure 1 is a view of the lock with the cover removed and showing the position of the parts after the dead bolt has been shot by the shut out key. Fig. 1^a is a view in section on the line *x-x* of Fig. 1. Fig. 2 is a view of the lock

40 with the dead bolt retracted and the latch bolt retracted by turning the knob in the direction of the arrow. Fig. 3 is a view showing the latch bolt retracted by turning the knob in the reverse direction. Fig. 4 is a view showing the action of the lifting or master key tumbler upon a change key tumbler through the swinging lifter. Fig.

45 5 represents the action of the lifter, change tumbler, and lifting fence tumbler, when operating a high bitted change tumbler by means of a low bitted master key. Fig. 6 shows the action of the shut out locking tumbler and guard slide when the bolt is shot by the shut out key. Fig. 7 shows the 50 shut out key as having shot the bolt and

just leaving the lifting or master tumbler and in contact with the shut out tumbler. Fig. 8 is a view showing the action of the shut out locking tumbler and guard slide when the bolt is shot by the shut out key. 60 Figs. 9, 10, and 11 are views respectively of the shut out, master and change keys, and Figs. 12 to 21 inclusive are views of parts detached.

1 represents a casing, 2 the latch bolt and 65 3 the knob spindle roll back provided with antifriction rollers 4 mounted on the pins 5. The rollers 4 are located above and below the horizontal center of the roll back with the upper one bearing against the spring 70 pressed pivoted lever 6 and the lower one against the pivoted lever 7. Lever 7 is pivoted to the lock case intermediate its ends, with one end in contact with the lip 8 at the tail end of the latch bolt 2, and is provided 75 adjacent its opposite end with a pin 9 carrying a roller which rests and moves in elongated slot 10 in lever 6. It will therefore be seen that the levers 6 and 7 are connected so that when one is moved, the other 80 will also be moved, hence when the knob roll back 3 is turned in one direction, as in Fig. 3^a, the upper roller 4 engages the upper lever 6 the movement of which moves the rear end of lever 7 rearwardly and retracts the latch 85 bolt, and when the knob roll back is turned in the opposite direction, as in Fig. 2, the lower roller 5 engages lever 7 and shifts its rear end rearwardly and thus retracts the bolt. The levers 6 and 7 are normally held 90 in contact with the rollers 4 and 5 by the spring 11, and the latch bolt 2 is normally held in projected position, by the pivoted lever 12 engaging pin 13 on bolt 2, and by the spring 14 which yieldingly holds the 95 lower end of lever 12 in contact with the pin 13. With this construction, there is no loose movement between the knob roll back and the latch bolt, and the roller contact between the parts reduces the friction and provides for an even and smooth movement from start to finish.

15 is the dead bolt, provided at its rear end with a key sweep, and intermediate its ends with the slot 16, through which the 105 post 17 on the lock case 1 projects, and mounted on the bolt 15, and movable therewith, is the spring pressed tumbler 18, carrying the fence 19. The rear end of this tumbler 18 rests on the shoulder 20 integral 110

with the rear end of the bolt, and is yieldingly held thereagainst by the spring 21, as clearly shown in Fig. 6.

Pivotedly mounted on the post 17 and resting in contact with the bolt 15 is the shut out locking tumbler 22 provided at its upper end with a laterally projecting finger 23, the function and operation of which will be disclosed later on. This tumbler 22 is also provided at its front edge with a bolt dead-locking projection 24, and at its lower end with a locking notch 25 adapted to receive a lip 26 at the lower end of the shut out locking fence 27, which latter is pivoted to the lock case and is operated by the shut out tumbler 30 shown detached in Fig. 16a.

Mounted on post 17, and in contact with the shut out locking tumbler 22 and the shut out locking fence 27, is the lifting tumbler 28, having an open center within which the swinging lifter 29 moves, the latter being pivotally attached at its front end to the lifting tumbler 28. This lifting tumbler 28 is provided at its lower front end with a headed pin 29a on which the shut out tumbler 30 is mounted, the said tumbler 30 having an inverted L-shaped slot 31a, through which the pin 29 passes, and which permits the tumbler 30 to have a pivotal, as well as an upward and downward and forward and backward sliding movement. This shut out tumbler 30, is also provided with a triangular opening about midway its length into and through which the pin 31 on the shut out locking fence 27 projects, so that when the tumbler 30 is actuated by the engagement of the shut out key during the first movement of the key in a direction to retract the bolt, the shut out locking fence 27 will also be actuated in one direction by the engagement of the wall of the opening in the tumbler 30, and when the tumbler 30, is actuated by the engagement of the shut out key after the bolt has been projected as shown in Fig. 7, the toe 32 on lever tumbler 30 will engage the lip 26 on shut out locking fence 27 and elevate said lip to release the lower end of shut out locking tumbler 22 with which it coöperates. This tumbler 30 is also provided with a pin 30a resting above and on the horn 28a of tumbler 28, so that when tumbler 28 is lifted, shut out tumbler 30 will also be lifted.

Mounted on the post 17 are a series of change key tumblers 33, which are actuated directly by the change keys which coöperate with the fence 19 on lifting fence-tumbler 18, and which are also engaged by the swinging lifter 29 carried by lifting tumbler 28. The upper or outer one of these change tumblers (shown in Fig. 14) is provided with two pins 34 and 35, on the upper one (34) of which is mounted the tumbler locking lever 36, provided at its front end with an inwardly bent end 37a, which latter

rests on and overhangs the entire series of tumblers. This lever 36 is L-shaped in plan, and is provided at its upper rear end with an elongated slot 37 through which passes the pin 38 rigidly secured to the lock case, 70 so that when the change tumblers are moved, the tumbler locking lever fulcrums on pin 38 and moves with the change tumblers.

Pivotedly mounted on pin 35 on the outer change key tumbler 33, is the locking lever dog 38, shown detached in Fig. 12. This lever is L-shaped and is adapted to be engaged by a step or bitting on the shut out key, and is provided at the free end of its upwardly projecting member, with a shoulder 39 adapted, under certain conditions, to engage the bent end 37a of tumbler locking lever 36, and prevent any of the tumblers from being raised by picking instruments or by any key other than the shut out key, 85 and this lever 38, is itself locked against movement, by the finger 23 of the shut out locking tumbler 22, which as shown in Fig. 1, rests in advance of locking lever dog 38, and when the dead bolt 15 has been projected by the shut out key, rests in contact with said dog 38 and holds same against movement.

40 is a guard slide located just above the dead bolt 15 and mounted on a stud 41 projecting from the lock case 1. Stud 41 passes through an elongated slot in the slide, and the latter is provided with a lip 42, projecting downwardly and resting in advance of a shoulder 43 on the dead bolt 15 100 so that during the forward movement of the bolt 15, when the latter is actuated by a change key, the shoulder 43 thereon coming in contact with the lip 42 shifts the slide forwardly. The slide is provided with a pin 44 engaged by a spring 45 secured to stud 41. As the slide 40 is moved by the bolt the pin 44 moves under the spring 45, and the lip 42 is therefore, always forced downwardly into the path of the shoulder 110 43 on the dead bolt. The locking lever dog 38, change tumblers 33 and tumblers 22 and 18 are each provided with a spring which tends to force them into their normal positions.

Having described the relative positions of the several parts of the dead bolt mechanism, I will now describe the operation of the lock.

Normally, and when the dead bolt is retracted, the lip 26 on the shut out locking fence 27 rests in advance of and against the front lower end of the shut out locking tumbler 22 and immediately over the toe 32 of shut out tumbler 30, as shown in Figs. 125 2 and 7. When a change key, shown in Fig. 11, is introduced and turned in a direction to project the bolt 15, its bitting engage all the change tumblers 33, and the lifting tumbler 28, and shifts them to a posi- 130

tion to permit the fence 19 on lifting fence tumbler 18 to move with the bolt. It also shifts the upper end of the locking lever dog 38 forwardly thus freeing the tumbler locking lever 36 and permitting the latter to move upwardly with the change tumblers. The movement of the lifting tumbler 28 by the key, also swings the shut out tumbler 30 rearwardly and upwardly, and the latter then operates, by the engagement of pin 31 with the lower wall of the opening in the shut out tumbler 30, to lift the shut out locking fence 27 so as to carry its lip 26 into a plane above the lower projecting end of the shut out locking tumbler 22, thus freeing the latter. Hence normally the locking fence 27 is in engagement with the front lower end of the shut out locking tumbler 22 and holds it in the position shown in Figs. 2 and 8, in which positions its bolt dead locking projection 24 is removed from the path of the bolt, and its lip 23 out of contact with the locking dog 38. As the change key is turned to project the bolt, the front end of tumbler locking lever 36 will be moved upwardly and into contact with the face 38^a of locking lever dog 38, the upper end of which latter will then be in contact with the lip 23 of shut out locking tumbler 22, and thus prevent any turning movement of the latter, under the influence of its spring during the time the lip 26 is out of contact with the lower front end of the shut out locking tumbler 22. As the bolt 15 is being projected these parts all go back to their normal position as shown in Fig. 2, thus leaving the bolt free to be retracted by any of the keys.

With the master key, shown in Fig. 10, the action is precisely as above described, except that the change tumblers are actuated by the center bitting of the master key engaging the lifting tumbler 28 which acting through its swinging lifter 29 elevates the change tumblers. When however, the shut out key (Fig. 9) is used to project the dead bolt, its long center tongue or bitting, engages lifting tumbler 28, and by means of the swinging lifter 29, elevates the change tumblers 33 so as to permit the bolt to be shot. At the same time the lifting tumbler 28 coming in contact with pin 44 on the guard slide 40, elevates the latter so as to carry the projection 42 on its lower edge, above the shoulder 43 on bolt 15, thereby permitting the bolt to move outwardly without moving the guard slide forwardly. As the key leaves the lifting tumbler, the center tongue or bitting of the shut out key comes into contact with the rear end of shut out tumbler 30 as shown in Fig. 7, and a continued rotation of the key in the direction of the arrow, forces the rear end of tumbler 30 down and its front end up, thus causing toe 32 at the front end of shut out

tumbler 30 to lift the front end of shut out locking fence 27 sufficiently high to release shut out locking tumbler 22, thus permitting the latter to turn under the influence of its spring so as to carry its dead locking projection 24 into the path of the bolt and positively dead lock the same, and also carry its lip 23 rearwardly and into contact with the front upper edge of the locking lever dog 38, thus holding the latter solidly down and in contact with the tumbler locking lever 36 as shown in Fig. 1. After the shut out key has passed and released the shut out tumbler, the shut out locking fence is forced down by its spring, and the lip 26 thereon entering the notch 25 in the shut out tumbler 22, positively locks the latter against movement and consequently deadlocks the bolts and locks every bolt locking tumbler against movement. After the parts have moved into the position last described, they can only be released and the bolt retracted by the shut out key, as the center tongues or bittings of the other keys are not long enough to engage and actuate the shut out tumbler 32.

To retract the bolt by the shut out key, the center tongue of the latter first engages the rear end of the shut out tumbler 30, and the lower wall of the opening in the latter acting against pin 31 on shut out locking fence 27, raises the front end of the latter until its lip 26 is clear of the notch 25 in shut out locking tumbler 22. This releases the latter and permits it to be moved forwardly against the action of its spring, by the forward movement of the front or vertical member of the locking lever dog 38 bearing against the lip 23 on said shut out locking tumbler 22. Dog 38 is positively elevated by the shut out key, hence as the key is turned to retract the bolt, after having passed the shut out tumbler 30, it first acts on dog 38 and moves it in a direction to release tumbler locking lever 36, and the continued movement thereof carries the upper end of tumbler 22 forwardly as above described, and also elevates the other tumblers so as to permit the fence 19 carried by the bolt to move rearwardly.

When the tumblers are actuated by a change key, the guard slide 40 is not lifted but is simply slid forwardly, as previously described by the contact of the shoulder 43 on the bolt, with the shoulder 42 on the slide and thus carries the lip 40^a, at the front end of said slide, up against pin 22^a on the shut out locking tumbler 22, and operates to prevent the shut out locking tumbler from falling onto the lever locking dog 38, during the movements of the shut out locking fence 27, as shown in Fig. 8. When however a shut out key is used, the lifting tumbler 28, makes contact with pin 44 on the guard slide and lifts same, thus permitting shoul-

der 43 on the dead bolt to pass under shoulder 42 on the guard slide. This leaves the shut out locking tumbler 22 free to fall onto the lever locking dog, the instant the lower 5 end of said tumbler is free of the shut out locking fence.

When the dead bolt is projected by the master or change key, it is not deadlocked by the projection 24 on the shut out locking tumbler 22, but the tumblers, are, when the bolt is projected by any key, and also when retracted, locked by the tumbler locking lever 36, and when the bolt is projected by the shut out key, this lever 36 is in turn 15 deadlocked by the shut out locking tumbler.

The center tongues or bittings on the shut out and change keys are of different lengths, yet each operates the lock perfectly for the reason that the tumbler work is set up for 20 the shorter tongue of the master key, and when the shut out key is used, the tumblers are first set to register properly with the fence, then tumblers and fence are all carried up together a distance equal to the difference in length of the two tongues.

When the master keys and change keys are used, the lower surfaces of the various tumblers represented by the letter α in Fig. 7 are carried up to such a height as to just 30 come under fence 19 on tumbler 18, but when the shut out key is used the long center tongue carries the lifting tumbler 28 to the high point and in so doing the surface α comes in contact with the lower face of the fence 19 and then carries the fence and the other tumblers up the extra distance without disturbing the relationship of the fence and the gatings of the several tumblers.

With the fence 19 on a pivoted tumbler, 40 it will be seen that when an attempt is made to lift the tumbler with a picker, the tumbler 18 and its fence 19 will also be lifted, thus rendering it exceedingly difficult if not impossible to line up the fence with the gatings in the tumbler. Again by means of the lifting fence tumbler, I am able to increase the number of changes in the change tumblers to an extent never heretofore attained.

In master keyed tumbler locks as at present constructed, no change key can be used which has any of its steps or bittings higher than that of the master key bitting which operates the lifter, but in this lock if a different master key is desired in order to provide a set of locks not operable by any of the keys of another set, the operating bitting can be shortened and in order to accommodate the tumbler work to this changed condition of the master key, a projection 45, 50 shown in Fig. 5 is added to the case to hold all the tumblers up in their normal position, and the lifting fence tumbler 18 is cut away as at 46 in order to let the fence 19 drop a distance equal to the amount cut off from 60 the master key, the same amount being also

cut off from the key sweeps of the change tumblers. With this construction the bolt when retracted may be freely projected by its change and master keys, the shut out locking tumbler 22 and shut out tumbler 30 70 remaining in inoperative position. When however the bolt is projected by a shut out key, the parts above referred to are brought into action and operate to lock the tumblers and the bolt against action by either the 75 change or master key.

It is evident that many slight changes might be resorted to in the relative arrangement of parts shown and described without departing from the spirit and scope of my 80 invention. Hence I would have it understood that I do not wish to confine myself to the exact construction and arrangement of parts shown and described, but

Having fully described my invention what 85 I claim as new and desire to secure by Letters-Patent, is:—

1. In a lock, the combination with a knob roll back carrying anti-friction rollers, a latch bolt and spring actuated devices for 90 projecting said bolt, of connected levers one of which engages the latch bolt, each lever pivoted to the lock case and located in the path of movement of the rollers on the roll back so as to be engaged thereby, whereby 95 a movement of the roll back in either direction from its normal position, actuates the levers in a direction to retract the latch bolt.

2. In a lock, the combination with a knob roll back, antifriction rollers carried by the 100 same, a latch bolt, and spring actuated means for projecting the bolt, of two levers each pivoted to the lock case and connected so as to move in unison, one of said levers 105 engaging the latch bolt for retracting the same, and each located in the path of movement of a roller on the roll back, whereby a rotation of the roll back in either direction actuates the levers in a direction to retract the bolt.

3. In a lock, the combination with a knob roll back carrying anti-friction rollers, a latch bolt and spring actuated devices for 110 projecting said bolt, of two connected levers each pivoted to the lock case and located in the path of movement of the rollers on the roll back so as to be engaged thereby, the free end of one of said levers directly engaging the latch bolt, whereby the latter will be retracted by the movement of said lever in 115 one direction.

4. In a lock, the combination with a knob roll back, antifriction rollers carried by said roll back, a latch bolt and spring actuated means for projecting the same, of two levers, 125 one pivoted between its ends with one end engaging a shoulder on the tail of the bolt for retracting same, the other pivoted at one end to the lock case and provided adjacent its opposite end with an elongated slot for 130

the reception of a pin carried by the adjacent end of the first mentioned lever, and a spring tending to hold the centrally pivoted lever out of contact with the tail of the 5 bolt, the said levers being in the path of movement of the rollers on the roll back, substantially as described.

5. In a multiple key lock, the combination with a dead bolt and tumblers adapted to be 10 operated by a plurality of keys including a shut out key, of means operable by the shut out key for locking the tumblers against movement.

6. In a multiple key lock, the combination 15 with a dead bolt, and tumblers adapted to be actuated by a plurality of keys including a shut out key, of means operable by the shut out key for locking the tumblers against movement and for deadlocking the bolt.

20 7. In a multiple key lock, the combination with a bolt, a series of tumblers actuated by a plurality of keys including a shut out key, and a shut out tumbler actuated only by the shut out key, of means controlled by the shut 25 out tumbler for locking the other tumblers against movement.

8. In a multiple key lock, the combination 30 with a bolt, a series of tumblers actuated by a plurality of keys including a shut out key, and a shut out tumbler actuated only by the shut out key, of means controlled by the shut out tumbler for dead locking the bolt.

9. In a multiple key lock, the combination 35 with a bolt, a series of tumblers actuated by a plurality of keys including a shut out key, and a shut out tumbler actuated only by the shut out key, of means controlled by the shut out tumbler for locking the other tumblers against movement and for deadlocking the 40 bolt.

10. The combination with a bolt carrying 45 a fence and a series of tumblers coöperating with said fence, of means for locking said tumblers against movement, and a shut out tumbler actuated directly by a key and adapted to control the movements of said tumbler locking means.

11. In a multiple key lock, the combination 50 of a bolt carrying a fence, a series of tumblers coöperating with said fence, a dead lock for the bolt, means for normally holding said deadlock in inoperative position the said means being actuated by one key of the series for releasing the dead lock and permitting same to move to deadlocking position, and means actuated by the same key for restoring the deadlock to its normal position.

12. In a multiple key lock, the combination 60 with a bolt, a series of change key tumblers, a lifting tumbler and a swinging lifter carried by said lifting tumbler and engaging the change key tumblers for lifting them, of means for locking the change key tumblers against movement and a shut out

tumbler operated by a key and controlling the positions and movement of the tumbler locking means.

13. In a multiple key lock, the combination with a bolt, a series of change key tumblers, a lifting tumbler and a swinging lifter carried by said lifting tumbler and engaging the change key tumblers for lifting them, of means for deadlocking the bolt, and a shut out tumbler carried by the lifting tumbler 70 and operated by a key for controlling the movements of the deadlocking means. 75

14. In a multiple key lock, the combination with a bolt, a series of change key tumblers, a lifting tumbler and a swinging lifter carried by said lifting tumbler and engaging the change key tumblers for lifting them, of means for locking the change key tumblers against movement, means for deadlocking the bolt, and a shut out tumbler carried by said 80 lifting tumbler and actuated by the direct engagement of a key therewith for controlling the movements of the tumbler locking devices and the bolt deadlocking means. 85

15. In a multiple key lock, the combination with a bolt, change key tumblers and a lifting tumbler, of a shut out locking tumbler for locking the change key tumblers against movement, a locking fence for said 90 shut out locking tumbler, and a shut out tumbler for moving said shut out locking fence out of contact with the shut out locking tumbler. 95

16. In a multiple key lock, the combination with a bolt, change key tumblers and a 100 lifting tumbler, of a shut out locking tumbler for locking the change key tumblers against movement and for deadlocking the bolt, a locking fence for said shut out locking tumbler, and a shut out tumbler for moving said shut out locking fence out of contact with the shut out locking tumbler. 105

17. In a multiple key lock, the combination with a bolt, change key tumblers and a lifting tumbler, the latter actuated by a shut 110 out key, of a shut out locking tumbler for locking the change key tumblers against movement and for deadlocking the bolt, a locking fence for said shut out locking tumbler, and a shut out tumbler carried by the 115 lifting tumbler and moved thereby and also moved by direct contact with the shut out key for moving said shut out locking fence out of contact with the shut out locking tumbler. 120

18. In a multiple key lock, the combination with a bolt, a series of change key tumblers and a lifting tumbler, of a tumbler locking lever, adapted to engage the tumblers for holding them against movement, a locking lever dog adapted to engage said tumbler locking lever, a shut out locking tumbler for holding the lever dog down onto the locking lever, a shut out locking fence for holding the shut out locking tumbler 125 130

against movement, and a shut out tumbler carried by the lifting tumbler for actuating the shut out locking fence.

19. In a multiple key lock, the combination with a bolt having a shoulder thereon, change key tumblers, a lifting tumbler, a shut out locking tumbler for locking the change key tumblers against movement, a shut out locking fence for the shut out locking tumbler and shut out tumbler actuated by the shut out key for controlling the movements of the shut out locking tumbler, of a guard slide mounted to tilt and slide on the lock case and provided with a shoulder on its underside to engage the shoulder on the bolt and with a lip at its front end to engage the shut out locking tumbler the said guard slide adapted to be slid forwardly by the bolt when the latter is actuated by a change key so as to carry its lip against the shut out locking tumbler and block the movement of the latter, and which will be tilted by the lifting tumbler so as to carry its shoulder out of the path of the shoulder on the bolt, when the parts are actuated by the shut out key, and then leave it in a position where it will not interfere with the free movements of the shut out locking tumblers.

20. The combination of a bolt, a lifting fence-tumbler carried thereby, a fence on said tumbler, change key tumblers and a

lifting tumbler actuated by a key for lifting the change key tumblers and also the lifting fence tumbler and its fence.

21. The combination of a bolt, a lifting fence-tumbler carried thereby, a fence on said tumbler, change key tumblers, a lifting tumbler actuated by a key for lifting the change key tumblers and also the lifting fence tumbler and its fence, and means for deadlocking the change key tumblers against movement.

22. In a multiple key lock, the combination with a dead bolt and tumblers adapted to be operated by a plurality of keys, of means actuated by all the keys of the series for locking the tumblers.

23. In a multiple key lock, the combination with a dead bolt and tumblers adapted to be actuated by a plurality of keys, of means actuated by all of the keys of the series for locking the tumblers, and means operated by one key of the series for deadlocking the tumbler locking means.

In testimony whereof, I have signed this specification in the presence of two subscribing witnesses.

EDWARD ROSE.
